WARNING SIGNAL

Lloyd Elmer Johnson, Fred William Billig, and
 Floyd W. Hardick, Jackson, Mich., assignors to
 The Sparks-Withington Company, Jackson,
 Mich., a corporation of Ohio

Application June 27, 1928, Serial No. 288,636

10 Claims.

(Cl. 177—7)

This invention relates to certain new and useful improvements in warning signals.

The main object of the invention is the production of an improved warning signal of pleasing and effective tone characteristics, and including the automatic production of a plurality of successive tones of varying pitch, and if desired of varying amplitude, preferably resulting in a succession of harmonious tones highly effective in attracting the attention of one to be warned.

Other objects and advantages relate to the structure of the apparatus and the details of the same, whereby the main object is accomplished, all as will more fully appear from the following description taken in connection with the accompanying drawings, in which:

Figure 1 is an elevation of a warning signal of this invention.

Figure 2 is a section on line 2—2, Figure 1.
 Figure 3 is a section on line 3—3, Figure 1.

Figure 4 is a section on line 4—4, Figure 1.

Figure 5 is a vertical section through one of the air resonant devices showing the cam-actuated valve for controlling the flow of air, taken on line 5—5, Figure 4.

Figure 6 is a section on line 6—6, Figure 4.

Figure 7 is a view similar to Figure 5 omitting the associated air resonant devices taken on line 7—7, Figure 4.

Figure 8 is a section similar to Figure 7 taken on line 8—8, Figure 4.

Figure 9 is a diagrammatic illustration of suitable circuits for the motor and automatic contact devices.

The structure as here illustrated comprises three air resonant devices of identical construction except for the shape of the projectors 1, 2, and 3 which are here shown of different lengths so as to produce tones of different pitch. These projectors may be of any suitable form to produce notes of desired amplitude and pitch, and any number of air resonant devices may be utilized.

Each air resonant device comprises in connection with the horn body 4 a tubular boss 5 in which the rear end of the respective projector is secured as by threaded relation. A tube 6 is secured in any suitable manner within a shoulered portion of the boss 5 as by a press-fit, and as shown, is aligned with the respective projector and projects rearwardly from the boss 5 and its exterior diameter is slightly less than the interior diameter of the boss so as to form an annular passageway surrounding the tube.

Further, the boss 5 has a circumferentially enlarged intermediate portion forming an annular chamber 7 surrounding tube 6 and this chamber is in communication with the respective one of the passageways 8, 9, and 10 leading through the 5 horn body and in communication with the air storage chamber 11 hereinafter more particularly described.

The rear end of boss 5 is interiorly enlarged with respect to the front end, and is threaded 10 for the reception of an exteriorly threaded tubular boss 12 formed concentrically at the base of a cup-shaped member 13 constituting the front wall of a diaphragm chamber. The boss 12 may be locked in any desired position with 15 respect to boss 5 as by means of a lock-nut 14. The internal diameter of the boss 12 is somewhat greater than the external diameter of the tube 6 so as to form an annular passageway around the tube 6 leading from chamber 7 to the 20 interior of the cup-shape member 13.

The annular wall of the cup-shape member 13 is externally threaded for cooperative engagement with the interiorly threaded flange upon a cup-shape cap 15 and this cap 15 is adapted to clamp between its end and the rear edge of the cup-shape member 13 a thin flexible metallic diaphragm 16. The size and arrangement of the parts is such that when the diaphragm 16 is positioned, as described, it extends across and normally closes the rear open end or mouth of tube 6 and preferably the rear open end of tube 6 is somewhat flared, as indicated.

It is found that the air in the chamber between diaphragm 16 and cap 15 varies in pressure somewhat in accordance with the temperature to which the device is subjected, thereby varying the pressure upon the diaphragm 16 which in turn affects the operation of the signaling device, and in order to maintain the device uniform in operation, the cap 15 is provided with one or more openings 17 to permit the entrance of air or the exit of air to or from the interior space.

The horn body 4 rests upon and is secured to a pump casing 18 in any suitable manner, as by screws or the like, and this pump casing, as shown, is of substantially circular form and is provided with an eccentrically positioned pump cylinder 19 having an inlet 20 in its base and an outlet 21 in its side wall leading to the storage chamber 11 disposed at one side of the pump cylinder 19. A rotor 22 including suitable blades 23 is positioned in the pump cylinder 19 and its rotor shaft is keyed or otherwise movably secured 50 55

for endwise movement to the armature shaft 24 of an ordinary motor A including the usual armature 26, field coils 27 and pole pieces 28.

The U-shaped motor frame 29 is secured in 5 any suitable manner, as by screws 30 to the flanges 31 formed integrally with the pump casing 18.

In the particular embodiment here illustrated 10 which includes three air resonant devices, the pump casing is formed with a similar number of passageways 31, 32, and 33 leading respectively to the passageways 8, 9, and 10, the respective valves 34, 35, and 36 controlling communication between the storage chamber 11 and the respective conduits or passageways 31, 32, and 33. Normally, the valves 34, 35, and 36 are held closed 15 to prevent the passage of air under pressure from the storage chamber to the respective air resonant device, as by means of the springs 37, 38, 20 and 39 respectively.

In order to operate the valves 34, 35, and 36 in 25 succession or in a pre-determined order, to cause actuation of the air resonant devices in pre-determined succession, the armature 24 is formed with a worm 40 meshing with a worm gear 41 secured to a counter-shaft 42 journaled in adjustable bearings in the flanges 31 so that rotation of the armature shaft will effect continued simultaneous rotation of the counter-shaft 42.

30 Mounted upon the counter-shaft 42 are a series of cams 43, 44, and 45 adapted for contact respectively with the lower ends of the stems of the valves 34, 35, and 36 so that upon rotation of counter-shaft 42, these cams in accordance 35 with their particular disposition and arrangement, will successively or in pre-determined order, elevate the respective valve against the action of its respective spring to open communication between the air storage chamber 11 and 40 the respective air resonant device to cause the production of a pre-determined signal and the production of a succession of varied tones in pre-determined order.

45 As here illustrated, the cam 43 is a double cam so that during each revolution it will elevate or open the valve 34 twice during each revolution. In the particular illustration here shown, the order of operation is as follows:—

50 Cam 45 is so disposed upon shaft 42 that it operates to open valve 36 shortly after the shaft 42 starts to rotate from a normal position. This valve remains open only momentarily and is then closed by its spring 30, whereupon cam 43 opens the valve 34 and this valve remains open 55 momentarily and is then closed by its spring 39.

Immediately thereafter, cam 44 opens valve 35 and this valve remains open momentarily and then closes, whereupon cam 43, due to its double nature, again opens the valve 34 and thereafter valve 34 closes. In this manner four successive notes are produced by the respective air resonant devices, one of which devices is operated twice at spaced intervals.

It will be obvious, however, that any desired 65 arrangement or order of actuation of the air resonant devices may be provided for.

In order to stop the operation of the apparatus after one complete rotation of counter-shaft 42, a disk 60 is provided mounted for rotation with 70 shaft 42 in any suitable manner, as upon a boss extending from the worm gear 41 and this disk is provided with a flattened surface, perhaps best shown in Figures 6 and 9, for cooperation with 75 a spring-bar 61 carrying contact 62. This

spring-bar, as well as its cooperating bar 63 may be mounted in any suitable manner insulated from each other, as for instance by screws 64 securing the bars to a portion of the pump casing in such a manner that the bar 61 is adapted 5 to ride upon the periphery of disk 60.

Normally bar 61 is tensioned downwardly so that contact 62 is spaced from contact 64 mounted on the bar 63 when bar 61 rests in normal position upon the flattened portion of the periphery of the disk 60.

When counter-shaft 42 is rotated, the rotation of disk 60 immediately elevates bar 61 and brings the contacts 62 and 64 together to close an electric circuit including the electric motor of the 15 device, and this condition will be maintained during one revolution of counter-shaft 42 and until the flattened portion of the periphery of disk 60 again comes to the position shown in Figures 6 and 9 where the tension of spring-bar 61 will 20 separate the contacts.

In operation, any suitable circuits may be utilized, as for instance those shown in Figure 9 in which motor A is connected in circuit with a source of potential, as battery B, and switch C 25 being provided for closing the circuit manually. In addition, a circuit is provided which electrically connects the two bars 61 and 63 and their contacts 62 and 64, such circuits shunting the switch C so that when contacts 62 and 64 are 30 brought together, the circuit through the motor A is closed, irrespective of the position of manual switch C. The operation will be readily understood in that the operator merely closes switch C, whereupon the armature of the motor begins 35 to rotate. Immediately upon its rotation, contacts 62 and 64 are brought together, and altho switch C is allowed to open, the motor will continue to operate until the flattened portion of the periphery of disk 60 again comes to the position 40 shown in Figs. 6 and 9, at which time the circuit is broken and the motor stops.

In order to assist in stopping the motor against its natural momentum when in motion, all of the valves 34, 35, and 36 are closed by their 45 springs just before the flattened portion of the edge of disk 60 comes to the position shown in Figure 6, where the circuit is broken, with the result that there is no outlet for the air from the storage chamber 11 and the resultant back pressure produced reacts upon the rotor 22 to stop rotation of the rotor, and the armature of the 50 motor practically instantaneously.

In order to start operation of the device a second time, it is again necessary for the operator to 55 close the switch C to initiate motor operation, whereupon the operation is automatic during one complete rotation of counter-shaft 42. The usual push-button switches utilized, as switch C, are provided with springs which break the circuit 60 upon the release of manual pressure and with such a switch in the circuits shown, contacts 62 and 64 act to complete the circuit during one rotation of the counter-shaft 42 if switch C is allowed to open after initiating motor operation. 65

Altho we have shown and described a specific structure including three air-resonant devices, and particular details of an apparatus for operation therewith, and for effecting such operation in definite order, we do not desire to restrict ourselves to any number of air-resonant devices or to any definite order of their operation, or to the details of the structure by which such operation is effected, as various and many changes may be made in each and all of the 70 75 80 85 90 95

same without departing from the spirit of the invention as set forth in the appended claims.

We claim:

1. A warning signal comprising a pump body, a plurality of air resonant devices supported thereon, an air compressor and an air storage chamber in the pump body adapted to receive air from the compressor, conduits leading from the air storage chamber to respective air resonant devices, valves in the pump body controlling the flow of air through the conduits, means for normally maintaining the valves closed, supporting means projecting from the pump body, a countershaft journaled in the supporting means and a plurality of cams mounted on said shaft for actuating the valves in predetermined order, a motor carried by the supporting means for driving said countershaft and said compressor, the axis of the armature shaft of the motor being normal to the axis of the countershaft, and means mounted on the countershaft for making and breaking the motor circuit.
2. A warning signal comprising a pump body, a plurality of air resonant devices supported thereon, an air compressor and an air storage chamber in the pump body adapted to receive air from the compressor, conduits leading from the air storage chamber to respective air resonant devices, valves in the pump body controlling the flow of air through the conduits, means for normally maintaining the valves closed, supporting means projecting from the pump body, a countershaft journaled in the supporting means and a plurality of cams mounted on said shaft for actuating the valves in predetermined order, one of said cams being adapted to actuate a valve a plurality of times during one cycle of operation of the countershaft, a motor carried by the supporting means for driving said countershaft and said compressor, the axis of the armature shaft of the motor being normal to the axis of the countershaft, and means mounted on the countershaft for making and breaking the motor circuit.
3. A warning signal of the air-operated type comprising a body member including a source of air under pressure a plurality of air resonant devices supported thereon, separate means of communication between each of the air resonant devices and the source of compressed air, a driving shaft to produce the air pressure, supporting means projecting from the body member, a countershaft disposed at substantially right angles to the driving shaft and journaled in the supporting means, driving connections between the two shafts, separate valves in the body member for controlling communication between the source of compressed air and the several air resonant devices, said valves each being associated with a separate operating rod, which rods extend substantially parallel with the driving shaft, a plurality of cams, equal in number to the operating rods and mounted on the countershaft for rotation therewith and movable in paths intersecting respective valve stems for moving said valves to open position in predetermined succession, and means carried by the supporting means for rotating the driving shaft.
4. A signaling device comprising a body having a pump chamber formed therein, a plurality of air resonant devices mounted on said body and having separate means of communication with said pump chamber, a pumping element in said chamber supporting means projecting from the body, an electric motor secured to said support-

ing means and including an armature shaft connected to said pumping element for actuating the latter, separate valves for controlling communication between the air resonant devices and the pumping chamber, a countershaft disposed at substantially right angles to said armature shaft and journaled in the supporting means, driving connections between the two shafts, separate cam elements mounted on said countershaft for opening said valves in predetermined sequence during rotation of the countershaft, and spring means for normally maintaining the valves closed.

5. A signaling device comprising a body member having a pump chamber formed therein, a plurality of air resonant devices mounted on said body, separate means of communication between the pump chamber and the respective air resonant devices, a pumping element in said chamber, an electric motor having its armature shaft connected to said pumping element, means for securing the electric motor to said body member, separate valves for controlling communication between the respective air resonant devices and the pumping chamber, a countershaft, bearings for said countershaft, means for securing said bearings to the pump body, driving connection between said countershaft and said armature shaft, separate cam elements mounted on said countershaft and adapted to open said valves in predetermined sequence during rotation of said countershaft, and spring means for normally maintaining the valves closed.

6. A signaling device comprising a body member having a pump chamber formed therein, a plurality of air resonant devices mounted on said body, separate means of communication between the pump chamber and the respective air resonant devices, a pumping element in said chamber, an electric motor having its armature shaft connected to said pumping element, means for securing the electric motor to said body member including a frame structure, separate valves for controlling communication between the respective air resonant devices and the pumping chamber, a countershaft, bearings for said countershaft supported in said frame structure, driving connection between said countershaft and said armature shaft, separate cam elements mounted on said countershaft and adapted to open said valves in predetermined sequence during the rotation of said countershaft, and spring means for normally maintaining the valves closed.

7. In a warning signal for automobiles, an air resonant device, means comprising a motor for supplying air to said resonant device to produce a warning signal, control means for stopping operation of said motor and means comprising a valve element associated with the air supply means for cutting off the air supply to said air resonant device before said motor is stopped, whereby a back-pressure of air is created to aid in stopping said motor.

8. In a warning signal for automobiles, a plurality of air resonant devices, means for supplying air to said air resonant devices in predetermined sequence comprising a plurality of valve elements, cam members for operating said air supply means and elements, motor means for operating said cam members and control means operative at a predetermined position of said cam members for automatically stopping the operation of the motor when all of the valves are in the closed position whereby a back-pressure of air is created to aid in stopping the motor.

9. In a warning signal for automobiles, a plurality of air resonant devices, means for supplying air to said resonant devices in predetermined sequence comprising a plurality of valve elements,
5 a motor and valve actuating means operatively connected with the motor for moving said valves into and out of the closed position, an electric circuit for operating said motor having a control switch therein, and means actuated by the motor
10 for automatically opening said switch to stop the motor when all the valves are in a closed position whereby a back pressure of air is created to aid in stopping the motor.
10. A warning signal, comprising a pump body,
15 a plurality of air resonant devices supported thereon, an air compressor and a storage chamber in the pump body, adapted to receive air from the compressor, conduits leading from the air

storage chamber to respective air resonant devices, valves in the pump chamber controlling the flow of air through the conduits, means for normally maintaining the valves closed, supporting means projecting from the pump body, a countershaft journaled in the supporting means, a plurality of cams mounted on said shaft for actuating the valves in predetermined order, a motor carried by the supporting means operatively connected with the countershaft and the compressor for driving said countershaft and said compressor, and means including a member mounted on the countershaft for maintaining the motor in operation during a complete cycle of rotation of said countershaft.
